UNITED STATES PATENT OFFICE

HARRY M. SCHAAE, OF YOUNGSTOWN, OHIO, ASSIGNOR TO TRUSCON STEEL COMPANY,
OF YOUNGSTOWN, OHIO, A CORPORATION OF MICHIGAN

TUNNEL LINER

Application filed August 28, 1930. Serial No. 478,492.

The object of the present invention is to provide a structure for lining tunnels, shafts, and the like, which can be readily produced in relatively simple parts and easily assembled, and which involves in such assembly, reinforcements and stiffening members that will effectively maintain the liner in position and against distortion, due to the pressure thereagainst.

10 A further and important object is to provide a structure of this kind that can be embedded in concrete in which case the reinforcing members interlock with the concrete, and thereby form a rigid connection between the shell or liner and the concrete body.

15 In the accompanying drawings several embodiments are illustrated by way of example, but it will be evident to those skilled in the art that other modifications within the scope 20 of the appended claims may be readily produced.

In said drawings:

Figure 1 is a sectional perspective view of a simple embodiment of the invention.

25 Figure 2 is a side elevation of the same.

Figure 3 is a similar view of a modification of the structure shown in Figure 1.

Figure 4 is still another embodiment of the invention.

30 Figure 5 is a structure slightly different from that shown in Figure 3.

Figure 6 is an embodiment of the invention in which a skeleton or lattice reinforcing member is employed.

35 Figure 7 is a side elevation of the same.

Figure 8 is a detail horizontal sectional view showing the splice employed in the inner member.

Figure 9 is a perspective view illustrating 40 the form of the splice.

Figure 10 is a perspective view of another form of skeleton or lattice reinforcement.

Figure 11 is a detail sectional view of the structure shown in Figure 1, indicating how

45 a centering or form may be applied for the purpose of filling with concrete behind the liner.

Considering the embodiment disclosed in Figures 1 and 2, plate members or sections 50 are employed of rolled steel or other metal of

channel form. Each of these consists of a main bearing wall 11 with side flanges 12. It will be understood that these sections are of material length and are longitudinally bowed or curved to the contour of the tunnel wall to which they are applied. Being independent members, they can be made in quantities and readily shipped.

Associated with them, is a reinforcing rib member. In Figure 1 this member is a T-bar, the rib proper being designated 13 with oppositely outstanding flanges 14 along one edge. The unflanged margin of this rib 13, it will be noted, is interposed between the immediate flanges 12 of two of the members 11 and is secured thereto by any suitable means, as for example, bolts 15 that pass through the flanges 12 and the rib 13. This provides an assembly of parts in which the plate members are effectively secured to the reinforcing rib member, so that the plate members are securely held in position and against distortion. It will be noted that this structure can be continued to form a lining of any length desired. The flanges 14 of the 70 reinforcing rib member serve to prevent any tendency of the rib member to bend laterally and furthermore these flanges may be perforated, as shown at 16 (see Fig. 11) to receive a centering wall or form, making it possible to embed the rib members in concrete and thus back the plate members 11. This centering, designated 17, in Figure 11, may be of any suitable material held to the flanges 14 by bolts 18, or other suitable fasteners that pass 80 through the openings 16.

In the structure shown in Figure 3, the plate sections are designated 11a and are of the same character as those already described. The reinforcing rib member in this 90 instance is shown as formed of two L-bars 13a flanged at their inner ends, as illustrated at 14a, and secured together by bolts 15a. The inner flanges 12a of the plates 11a are shown as secured by bolts 16a to the rib members 13a, though other suitable fasteners may be employed. It will be evident that other shapes than L-bars may be utilized.

Referring now to the form of construction shown in Figure 4, the plate members are 100

designated 11b and are of the type already considered, being provided with longitudinal side flanges 12b. The reenforcing rib member in this structure is shown as formed of two L-bars 13b bolted together as illustrated at 15b, and having their inner portions provided with flanges 14b. The outer sides of these bars are outset, thereby providing a longitudinal channel 16b in which the inner side flanges of the plates 11b are snugly received and are held by bolts 17b or otherwise suitably fastened.

The structure disclosed in Figure 5 is much like that shown in Figure 1, except that two flat plates 13c are employed for the reenforcing rib member, these plates being interposed between the inner flanges 12c of the plate members 11c and bolted thereto as illustrated at 15c.

In the structure illustrated in Figures 6-9 inclusive, a skeleton reenforcing member is employed. The same plate members, designated here 11d with their side flanges 12d are employed. The reenforcing rib member, however, consists of an outer chord 13d and an inner chord. This inner chord may consist, for example, of two angle bars 14d spot welded or otherwise secured together. The outer and inner chords are connected by a lattice which may be in the form of a zigzag rod 15d electrically welded at its bends to the inner and outer chords. The outer chord has the adjacent flanges 12d of the plate members 11d lying against its opposite faces, and secured by bolts 16d or other suitable fasteners. In this structure the reenforcing rib member is preferably of sections that are spliced together. The outer chord 13d may have its ends abutted and these ends will of course to be secured together by the flanges 12d of the plate members bolted thereto, which extend across the joint. The inner chord preferably has one of its angle bars terminating short of the other on one side at one end, and correspondingly extended on the other end (see Figure 9). These extended ends designated 17d can therefore be lapped and secured together by bolts 18d or other fasteners.

Finally as an additional illustrative form the structure shown in Figure 10 may be considered. Here again there is employed the plate members, designated 11e with their side flanges 12e. The reenforcing rib member is a skeleton or lattice beam. The outer side is of channel form, and is designated 13e, having side flanges 14e bolted or secured by other suitable fastening means to the inner side flanges 12e, the bolts being shown at 15e. The inner chord member is shown as of angle bars 16e, bolted together at 17e. The lattice structure that joins the inner and outer chords is designated 18e and is shown as extending from each of the angle bars 16e to the side flanges 14e of the outer chord.

It will be evident that a lining structure for tunnel, shafts, or other work of an analogous character can be built up of parts, easily and cheaply manufactured and can be assembled to produce a liner that is exceptionally strong and rigid and which can be used with or without concrete as may be found desirable.

From the foregoing, it is thought that the construction, operation and many advantages of the herein described invention will be apparent to those skilled in the art, without further description and it will be understood that various changes in the size, shape, proportion and minor details of construction may be resorted to without departing from the spirit or sacrificing any of the advantages of the invention.

What I claim, is:

1. A lining structure of the character set forth, comprising a reinforcing bar having a web provided with an unflanged outer side, liner plates on opposite sides of the bar having integral side flanges of less width than the width of the bar and lying against the opposite faces of the outer unflanged portion of the web of said bar, and fasteners securing the said integral flanges of the plates to the unflanged portions of the bar, the inner portion of said bar projecting inwardly beyond the inner edges of the integral side flanges of the plates.

2. A lining structure of the character set forth, comprising a reinforcing bar of reverse T-form having its inner portion laterally flanged, and its outer portion unflanged, liner plates on opposite sides of the bar, having integral side flanges of less width than the width of the bar and lying along the outer unflanged portion of the same, and means for directly fastening the said integral flanges of the plates to the outer unflanged portion of the bar, the flanged inner portion of the bar extending inwardly beyond the flanges and with the plates forming a substantially I-beam structure.

A tunnel liner structure comprising a series of associated and connected plates forming a substantially continuous outer wall and a reinforcing bar for the plates secured thereto and including outer and inner chords, and a skeleton web connecting the chords, the web and inner chord being located at and projecting beyond the inner side of the liner wall and plates.

4. A lining structure of the character set forth comprising a reenforcing rib member, consisting of a beam having an outer chord and an inner chord with a skeleton lattice connecting the same, plate sections having marginal flanges lying along one of the chords, and means securing said flanges and chord together.

5. A lining structure of the character set forth, comprising a reenforcing rib member

consisting of a beam longitudinally channeled and having a substantially U-shaped outer chord, an inner chord, a skeleton lattice connecting the inner and outer chords,
5 plate sections having marginal flanges lying along the outer chord, and means securing said flanges and chord together.

In testimony whereof, I affix my signature.
HARRY M. SCHaab.
